E. E. CLARK

SELVAGE MOTION FOR AXMINSTER LOOMS

Filed March 6, 1925

Fig. 1.

Everett E. Clark Inventor

Southgate Fays & Hawley
Attorneys

UNITED STATES PATENT OFFICE.

EVERETT E. CLARK, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SELVAGE MOTION FOR AXMINSTER LOOMS.

Application filed March 6, 1925. Serial No. 13,552.

This invention relates to selvage motions for looms and more particularly to such a motion for Axminster or other carpet looms.

It is the principal object of my invention to provide a selvage motion which may be operated from a regularly moving part of the loom such as the lay so as to render unnecessary the addition of extra operating parts.

10 It is a further object of my invention to provide a selvage motion operated by the lay wherein the selvage threads will be in the upper part of the shed for one beat and will be in the lower part of the shed for the next beat. The lay has a complete cycle of motion for each pick of the loom, but the selvage thread must be raised for one pick and lowered for the next. It is necessary, therefore, to introduce some intermediate 20 device between the lay and the selvage motion which will convert the one pick motion of the lay to the two pick motion necessary for the selvage motion.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a side elevation of the right hand end of an Axminster loom having my invention applied thereto.

35 Fig. 2 is an enlarged fragmentary view of certain parts shown in Fig. 1 and showing the operating mechanism for the selvage needle, and

Fig. 3 is a vertical section on line 3—3 of Fig. 2.

Referring more particularly to the drawings it will be seen that I have provided a frame 10 on which is supported a cam shaft 11 to which is secured a cam 12 having cam

45 points 13. An upright cam lever 14 is pivoted as at 15 to some fixed part of the loom and has a roll 16 thereon positioned for operative engagement with the cam points 13.

50 The upper end of said lever 14 is pivotally connected as at 17 to a link 18 which is connected as at 19 to the lower end of lever 20 secured to lay shaft 21. Upstanding from the lay shaft 21 and secured thereto is a reed 22 by means of which the filling

may be beaten into the fell of the cloth. 55 The shaft 11 and cam 12 rotate at such a speed that the reed 22 is given a forward movement each pick of the loom. The mechanism thus far described is of common construction and forms no part of my present invention.

It is the principal object of my invention to provide a selvage motion which may be operated from a regularly moving part of the loom such as the lay so as to render unnecessary the addition of extra operating parts.

10 It is a further object of my invention to provide a selvage motion operated by the lay wherein the selvage threads will be in the upper part of the shed for one beat and will be in the lower part of the shed for the next beat. The lay has a complete cycle of motion for each pick of the loom, but the selvage thread must be raised for one pick and lowered for the next. It is necessary, therefore, to introduce some intermediate 20 device between the lay and the selvage motion which will convert the one pick motion of the lay to the two pick motion necessary for the selvage motion.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a side elevation of the right hand end of an Axminster loom having my invention applied thereto.

35 Fig. 2 is an enlarged fragmentary view of certain parts shown in Fig. 1 and showing the operating mechanism for the selvage needle, and

Fig. 3 is a vertical section on line 3—3 of Fig. 2.

Referring more particularly to the drawings it will be seen that I have provided a frame 10 on which is supported a cam shaft 11 to which is secured a cam 12 having cam points 13. An upright cam lever 14 is pivoted as at 15 to some fixed part of the loom and has a roll 16 thereon positioned for operative engagement with the cam points 13. The upper end of said lever 14 is pivotally connected as at 17 to a link 18 which is connected as at 19 to the lower end of lever 20 secured to lay shaft 21. Upstanding from the lay shaft 21 and secured thereto is a reed 22 by means of which the filling

may be beaten into the fell of the cloth. 55 The shaft 11 and cam 12 rotate at such a speed that the reed 22 is given a forward movement each pick of the loom. The mechanism thus far described is of common construction and forms no part of my present invention.

It is the principal object of my invention to provide a selvage motion which may be operated from a regularly moving part of the loom such as the lay so as to render unnecessary the addition of extra operating parts.

10 It is a further object of my invention to provide a selvage motion operated by the lay wherein the selvage threads will be in the upper part of the shed for one beat and will be in the lower part of the shed for the next beat. The lay has a complete cycle of motion for each pick of the loom, but the selvage thread must be raised for one pick and lowered for the next. It is necessary, therefore, to introduce some intermediate 20 device between the lay and the selvage motion which will convert the one pick motion of the lay to the two pick motion necessary for the selvage motion.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a side elevation of the right hand end of an Axminster loom having my invention applied thereto.

35 Fig. 2 is an enlarged fragmentary view of certain parts shown in Fig. 1 and showing the operating mechanism for the selvage needle, and

Fig. 3 is a vertical section on line 3—3 of Fig. 2.

Referring more particularly to the drawings it will be seen that I have provided a frame 10 on which is supported a cam shaft 11 to which is secured a cam 12 having cam points 13. An upright cam lever 14 is pivoted as at 15 to some fixed part of the loom and has a roll 16 thereon positioned for operative engagement with the cam points 13. The upper end of said lever 14 is pivotally connected as at 17 to a link 18 which is connected as at 19 to the lower end of lever 20 secured to lay shaft 21. Upstanding from the lay shaft 21 and secured thereto is a reed 22 by means of which the filling

may be beaten into the fell of the cloth. 55 The shaft 11 and cam 12 rotate at such a speed that the reed 22 is given a forward movement each pick of the loom. The mechanism thus far described is of common construction and forms no part of my present invention.

It is the principal object of my invention to provide a selvage motion which may be operated from a regularly moving part of the loom such as the lay so as to render unnecessary the addition of extra operating parts.

10 It is a further object of my invention to provide a selvage motion operated by the lay wherein the selvage threads will be in the upper part of the shed for one beat and will be in the lower part of the shed for the next beat. The lay has a complete cycle of motion for each pick of the loom, but the selvage thread must be raised for one pick and lowered for the next. It is necessary, therefore, to introduce some intermediate 20 device between the lay and the selvage motion which will convert the one pick motion of the lay to the two pick motion necessary for the selvage motion.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a side elevation of the right hand end of an Axminster loom having my invention applied thereto.

35 Fig. 2 is an enlarged fragmentary view of certain parts shown in Fig. 1 and showing the operating mechanism for the selvage needle, and

Fig. 3 is a vertical section on line 3—3 of Fig. 2.

Referring more particularly to the drawings it will be seen that I have provided a frame 10 on which is supported a cam shaft 11 to which is secured a cam 12 having cam points 13. An upright cam lever 14 is pivoted as at 15 to some fixed part of the loom and has a roll 16 thereon positioned for operative engagement with the cam points 13. The upper end of said lever 14 is pivotally connected as at 17 to a link 18 which is connected as at 19 to the lower end of lever 20 secured to lay shaft 21. Upstanding from the lay shaft 21 and secured thereto is a reed 22 by means of which the filling

may be beaten into the fell of the cloth. 55 The shaft 11 and cam 12 rotate at such a speed that the reed 22 is given a forward movement each pick of the loom. The mechanism thus far described is of common construction and forms no part of my present invention.

It is the principal object of my invention to provide a selvage motion which may be operated from a regularly moving part of the loom such as the lay so as to render unnecessary the addition of extra operating parts.

10 It is a further object of my invention to provide a selvage motion operated by the lay wherein the selvage threads will be in the upper part of the shed for one beat and will be in the lower part of the shed for the next beat. The lay has a complete cycle of motion for each pick of the loom, but the selvage thread must be raised for one pick and lowered for the next. It is necessary, therefore, to introduce some intermediate 20 device between the lay and the selvage motion which will convert the one pick motion of the lay to the two pick motion necessary for the selvage motion.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a side elevation of the right hand end of an Axminster loom having my invention applied thereto.

35 Fig. 2 is an enlarged fragmentary view of certain parts shown in Fig. 1 and showing the operating mechanism for the selvage needle, and

Fig. 3 is a vertical section on line 3—3 of Fig. 2.

Referring more particularly to the drawings it will be seen that I have provided a frame 10 on which is supported a cam shaft 11 to which is secured a cam 12 having cam points 13. An upright cam lever 14 is pivoted as at 15 to some fixed part of the loom and has a roll 16 thereon positioned for operative engagement with the cam points 13. The upper end of said lever 14 is pivotally connected as at 17 to a link 18 which is connected as at 19 to the lower end of lever 20 secured to lay shaft 21. Upstanding from the lay shaft 21 and secured thereto is a reed 22 by means of which the filling

and will be drawn to the right by spring 35 until it engages the tip 51, at which time further movement of the roll to the right will be arrested. As the lay recedes finger 44 will be lowered to permit spring 39 to lower the lever 30 and when the roll 34 passes below the tip 51 it will be at the lowest part of the recess 52. Any tendency on the part of spring 35 to move said roll 10 out of the recess will be resisted by the downward pull of the relatively stronger spring 39 and the roll and link 33 will therefore be held in raised position until after the next shot of filling has been laid.

15 On the next forward beat of the lay the finger 44 will again raise lever 30 and the spring 35 will act to draw the roll 34 to the right of tip 51 causing said roll to pass over the horn 55 of the switch and down the 20 right hand face 56 of the switch. As the lay moves rearwardly spring 39 will lower the link and said roll will move the switch to the left against the pressure of spring 49 until said roll again assumes the position 25 shown in Fig. 1. The needle 37 moves with the roll and the warp thread S is thus moved from lower to upper position during one complete beat of the lay and from upper back to lower position on the succeeding 30 beat of the lay.

It will thus be seen that I have provided a switch cam and link which is operated at every forward beat up of the lay but the arrangement is such that the needle 37 will 35 be in raised position on alternate beats and in lowered position on the intermediate beats of the lay. This result is accomplished by reason of the fact that the tip 51 prevents the link 33 from moving over the horn 55 40 when link 33 is being raised by finger 44.

Having thus described my invention it will be apparent that changes and modifications may be made therein by those skilled in the art without departing from the spirit and 45 scope of the invention; and I do not wish to be limited to the details herein disclosed, but what I claim is:

1. In a selvage motion for looms, a needle to move the selvage thread, a lay, and operative connections between the lay and the 50 needle to raise said needle on one forward motion of the lay and to lower said needle on the next forward motion of the lay.

2. In a selvage motion for looms, a lay, 55 a needle to move the selvage thread, means to raise said needle on the forward beat of the lay, and retain said needle in raised position, and means to lower said needle on the next forward beat of the lay.

3. In a selvage motion for looms, a lay, 60 a needle to move the selvage thread, means to raise the needle on the forward beat of the lay, means to retain the needle in raised position as the lay recedes, and means to lower the needle on the next forward beat of the 65 lay.

4. In a selvage motion for looms, a lay, 70 a needle to move the selvage thread, means actuated by the lay to raise and lower said needle, and a controller for said needle, said controller holding the needle raised after the latter has been lifted by the means on one forward beat of the lay and said controller operating to lower said needle on the next forward beat of the lay. 75

5. In a selvage motion for looms, a lay, 80 a selvage thread needle, and operative connections between the lay and needle to raise said needle on one beat of the lay and lower said needle on the next beat of the lay, said 85 connections including a yieldingly mounted lever, a link yieldingly pivoted to said lever, a fixed stop for the link, and a guide for said link, the guide moving the link to have operative contact with the stop on one beat 90 of the lay when raising the needle and said guide moving the link out of operative contact with the guide on the next beat of the lay to lower the needle.

6. In a selvage motion for looms, a lay, 90 a selvage thread needle, and operative connections between the lay and the needle to raise said needle on one beat of the lay and lower said needle on the next beat of the lay, said connections comprising a lever pivoted to a fixed part of the loom, and connected to the needle, means moving with the lay to raise the lever and needle, a link pivotally connected to the lever, a fixed stand, 95 a guide pivotally mounted on the stand and yieldingly held in normal position, a stop on the stand opposite a depression in the guide, a projection extending from the link to have operative contact with the stand, stop thereon and guide, yielding means to move the projection against said stop as the lever is raised, yielding means connected to the lever and acting against the means moving with the lay to lower the projection into the recess in the guide as said means moving with the lay is lowered; said yielding means to move the projection moving the latter out of the recess and clear of said stop when the lever is next raised. 105

In testimony whereof I have hereunto af- 110 fixed my signature.

EVERETT E. CLARK,
